GOVERNOR CONTROL MECHANISM

Elmer McCormick, Waterloo, Iowa, assignor to
 John Deere Tractor Company, Waterloo, Iowa,
 a corporation of Iowa

Application August 22, 1935, Serial No. 37,281

11 Claims. (CL 264—3)

The present invention relates generally to tractors and similar machinery and is principally concerned with the provision of a new and improved governor control mechanism whereby the action of the tractor governor is made more accurate and the speed of the tractor motor can be kept more nearly uniform than has heretofore been practical.

Farm tractors and the like are usually supplied with governors suitably connected with the throttle valve of a carburetor and adjustable spring means so as to automatically maintain the correct engine speed under varying load conditions, adjustment of the spring tension serving to cause the motor to run faster or slower. However, in prior structures of which I am aware, the various forms of linkage employed have embodied springs and other parts movable on or within one another during the action of the governor in adjusting the position of the carburetor throttle to maintain uniform engine speed. In order to keep the governor linkage parts from binding and to prevent variations due to friction of the associated parts from affecting the action of the engine, it was necessary to frequently examine the linkage in order to keep the parts free from dirt and to correct for any binding or friction at any point from the opening to the closing position of the carburetor throttle.

With these factors in mind, the principal object of the present invention contemplates the construction and arrangement of a governor control linkage so that the possibility of binding and excessive friction is entirely eliminated without in any way affecting the sensitiveness of the control by the engine governor. Specifically, it is an object of the present invention to provide spring biasing means, against which the governor normally acts, so arranged and constructed that the spring is connected directly with the governor arm and with the manually set lever by a simple pivotal connection, whereby practically all friction is eliminated and no unnecessary sliding of one part on another is present.

Still further, another object of the present invention contemplates the use of a spring means so constructed and connected with the manually adjustable part that the reaction of the spring bias against the governor arm is taken by bearing surfaces in alignment with the direction of the force of the spring. This serves to eliminate all tendency for cocking of one part with respect to the other and otherwise eliminates excessive and uneven wear due to eccentrically applied forces. An additional object of the present in-

vention in this connection is the use of a flat leaf spring firmly anchored to the governor arm at one end and by a simple rod connection to the adjustable parts which determine the speed of the engine.

These and other objects and advantages of the present invention will be apparent to those skilled in the art after a consideration of the following description of the preferred structural embodiment of the principles of the present invention, taken in conjunction with the accompanying drawing illustrating such embodiment.

In the drawing:

Figure 1 is a top plan view of a portion of the power plant and associated parts of a farm tractor of the two cylinder horizontal type and embodying the present invention;

Figure 2 is a section taken along the line 2—2 of Figure 1;

Figure 3 is a section taken along the line 3—3 of Figure 2;

Figure 4 is an enlarged plan view of the governor arm and associated leaf spring; and

Figure 5 is a section taken substantially along the line 5—5 of Figure 1, with certain parts shown in elevation.

Referring now more particularly to Figures 1 and 2, the reference numeral 10 indicates the tractor motor in its entirety. The motor 10 is provided with a combined crank case and transmission housing 11 in which is journaled the motor crank shaft upon which the fly wheel 12 is mounted. On the end opposite the fly wheel 12, the crank shaft carries a belt pulley 13. The motor 10 is provided with a manifold 15 to which is connected a carburetor 16 of conventional construction and provided with a throttle valve 17.

The governor mechanism for the tractor is indicated in its entirety by the reference numeral 20 and includes a governor housing 21 mounted on the top of the motor block 11, as best shown in Figure 2, by any suitable means, such as bolts or cap screws 22. The present invention is not particularly concerned with the details of the governor itself, and it will therefore suffice to note that a shaft 25 is journaled within the housing 21 upon bearings 26 and 27 and carries at one end a pinion 28 which meshes with a gear 29 connected with or forming a part of the transmission system of the tractor so as to be driven at a speed proportional to the speed of rotation of the engine. Fixed to the shaft 25 is a gear 30 which not only serves to drive a fan shaft 31 (Figure 1) but is provided with ears 33 which

pivotedly receive the bell crank levers 34 on which the governor weights 35 are fixed. The inner ends 37 of the bell crank levers 34 are rounded, as best shown in Figure 2, so that as the shaft 25 rotates the weights 35 swing outwardly under centrifugal force and cause the inner ends 37 of the bell crank levers 34 to press against the adjacent end of a sleeve 40 slidably mounted on the shaft 25. This motion is transmitted by means of a thrust bearing 41 to the rounded bifurcated end 42 of an arm 43 mounted on a vertically disposed governor shaft 44, the upper end of which projects out through the top of the governor housing 21. The arm 43 is preferably secured to the governor shaft 44 by means of screws 45, and the vertically disposed shaft 44 is journaled for rocking motion in bosses 47 and 48 formed in the housing 21.

The governor arm, that is, the member movable in response to variations in the speed of rotation of the motor 10, is indicated in its entirety by the reference numeral 50 and comprises a rigid section 51 having an apertured boss 52 at its inner end the opening 53 of which is adapted to receive the upper end of the governor shaft 44. The other part of the governor arm 50 consists of a flat leaf spring 55 having a long taper and mounted at its inner end in a notch or groove 56 extending generally longitudinally of the governor arm section 51. Preferably, the inner end of the spring 55 fits snugly within the side wall portions of the groove 56 and is held fixedly in place therein by a spring clamp 58. Both the inner end of the spring 55 and the spring clamp 58 are provided with an opening formed therein to receive a set screw 60 which is threaded into another opening 61 formed in the boss portion 52 of the rigid governor arm 51 and intersecting the opening 53. A nut 62 threaded onto the outer portion of the set screw 60 serves to securely hold the spring clamp 58 and the spring 55 in position, the set screw 60 serving to fixedly secure the governor arm 50 to the upper end of the governor shaft 44 so as to swing with the latter. A projection 65 is formed on the outer end of the governor arm 51 at substantially right angles to the axis of the arm and is engageable with the outer end portion of the spring 55 so as to limit the relative movement between the parts 51 and 55 in one direction, and the outermost end of the spring 55 is formed with an eye 66 to receive one end of a rod 67. Similarly, the outermost end of the rigid governor arm section 51 is provided with an opening to receive an end of another rod 69.

As best shown in Figure 1, the rod 67 is utilized as a connection between the outermost end of the spring 55 and a hand throttle unit 70 mounted on a bracket 71 carried at the upper end of the steering column 12 (Figure 5) of the tractor. The hand throttle unit includes an arm 73 which is adapted to be adjustably mounted so as to be retained in any position to which it may be moved for the purpose of determining the speed of the tractor motor. Preferably, the hub 70a of the lever 70 is arranged to fit into a tapered socket formed in the bracket 71, and a spring 76 is biased between the upper end of the spindle portion of the arm 73 and the bracket 71 for the purpose of maintaining frictional engagement between the lever 70 and the bracket 71. The outer end of the arm 73 is provided with an opening to receive the angularly bent end of a sleeve member 74 which is mounted upon the threaded end 75 of the rod 67 and

thereby serves as a part of the latter. The end of the rod 67 opposite the end 75 and the part 74 thereof is also bent angularly, as at 77 in Figure 2, and this latter end is disposed in the eye 66 at the outermost end of the spring 55. Suitable washers and cotter keys 78 are preferably employed for holding the spring and rod in proper position.

The governor arm 51 is connected with the throttle valve 17, as aforesaid, by the rod 69, and the rear end of this member is bent angularly and by this means is pivoted to the outer end of the throttle arm 17. The opposite or forward end of the rod 69 carries a fitting or sleeve member 80 which is similar to the member 74 described above and is also provided with an angularly bent end 81, a lock nut 82 being disposed on the threaded end of the rod 69 for the purpose of locking the member 80 in adjusted position. The member 74 on the rod 67 is similarly secured in adjusted relation on the rod 67.

In operation, the governor weights 35 move outwardly in proportion to the rate of rotation of the shaft 25, rocking the shaft 44 and the governor arm 50. The spring 55, anchored to the hand throttle unit 70 by the rod 67, exerts a bias resisting the rocking of the shaft 44 and arm 51 and, in connection with the setting of the hand throttle unit 70, determines the amount of rocking movement which the rigid governor arm section 51 experiences for a given rate of speed of the engine 10. Swinging movement of the arm 51, which is in the direction of the arrow shown in Figure 1 as the spring 55 yields, causes the throttle valve 17 to move towards its closed position. By virtue of this construction, when the tractor is operating under load the speed of the engine remains substantially constant, for as the load lightens and the motor tends to speed up, the weights 35 move outwardly and swing the arm 51 in a counterclockwise direction as viewed in Figure 1, thus partially closing the throttle valve 17. The extent of closing depends, of course, upon the setting of the hand lever 70, for this unit is capable of adjustment to impose greater or less tension in the spring 55 which is anchored to the arm 51. When the engine is at rest and the spring 55 swings the arm 51 clockwise, as viewed in Figure 1, the projection 65 engages the spring so as to limit any further movement of the arm 51 in this direction, the projection 65 thereby serving as a stop, acting through the rod 67 and the hand lever unit 70, for limiting the position of the governor arm. Adjustments of the parts 74 and 80 thereby determine the relative position of the hand throttle 70 and the full open position of the throttle 17, respectively, it being noted from Figure 2 that in the retracted position of the governor balls 35 the inner ends 37 of the bell cranks 34 engage the hub of the pinion gear 30.

From the above description, it will be apparent that the governor control linkage that I have provided practically eliminates all binding and friction, since there are no parts sliding on one another, nor are there any parts which tend to trap and retain dirt and the like. Thus, the governor action of the tractor provided with the present invention is smooth and the speed control is accurate, sensitive and uniform. It is also to be noted that in the case of both of the rods 67 and 69 the ends are bent in the same direction, namely, at right angles to the main body of the rod in each case, and the particular advantage of this arrangement is that the center 76

of pressure and the center of reaction of the forces imposed are in alignment with the direction of force. This is especially advantageous in the case of the rod 67 against which the tension 5 of the spring 55 acts, for where the points of bearing are arranged in this manner, there is no tendency or uneven wear to occur either on the ends of the rod or the apertured members with which the rod is connected.

10 While I have shown and described above the structure in which the principles of the present invention have preferably been embodied, it is to be understood that my invention is not to be limited to the specific details shown and described, but that, in fact, widely different means 15 may be employed in the practice of the broader aspects of my invention.

What I claim, therefore, and desire to secure by Letters Patent is:

1. Governor control mechanism for a tractor or the like having a speed responsive governor and a carburetor, said mechanism comprising a throttle rod connected with the carburetor, a governor actuated arm mounted for pivotal movement on the tractor and connected at its outer end with the throttle rod, a leaf spring anchored at its inner end to said governor actuated arm adjacent the pivot axis of the latter, a stop carried by the outer end of said arm and engageable with the leaf spring to limit the relative movement between the arm and spring in a direction to determine the open position of the throttle valve, and a manually set lever connected with the outer end of said leaf spring member to govern the bias imposed on said governor arm by said spring when said arm is moved to close said throttle valve.

2. Governor control mechanism for a tractor or the like having a speed responsive governor including a governor shaft and a carburetor including a throttle valve, said mechanism comprising a throttle rod connected at one end with said valve, a governor actuated arm including a boss at one end apertured to receive said governor shaft and having a longitudinally extending notched section with a threaded opening formed therein, a set screw disposed in said threaded opening and said notch and adapted when tightened to securely fasten the governor arm to said governor shaft, means connecting the throttle rod with the outer end of said governor arm, whereby the position of the latter determines the throttle opening of the carburetor, a flat leaf spring having an apertured inner end seated in said notch, the opening in the spring embracing said set screw, a spring clamp disposed in said notch against the inner end of said leaf, a nut threaded over said set screw and acting against said spring clamp for securing said leaf spring to said arm, a manually adjustable lever movably mounted on the tractor and adapted to retain any position of adjustment, and a rod member connected between said manually adjustable lever and the outer end of said spring.

3. Governor control mechanism for a tractor or the like having a speed responsive governor including a governor shaft and a carburetor including a throttle valve, said mechanism comprising a throttle rod connected at one end with said valve, a governor actuated arm apertured to receive said governor shaft and having a threaded opening formed therein, a set screw disposed in said threaded opening and adapted 75 when tightened to securely fasten the governor

arm to said governor shaft, means connecting the throttle rod with the outer end of said governor arm, whereby the position of the latter determines the throttle opening of the carburetor, a flat leaf spring having an apertured inner 5 end embracing said set screw, a nut threaded over said set screw and acting against said leaf spring for securing the same to said arm, a manually adjustable lever movably mounted on the tractor and adapted to retain any position of 10 adjustment, and a rod member connected between said manually adjustable lever and the outer end of said spring.

4. An article of manufacture comprising a governor arm having an apertured boss and a 15 spring receiving groove at one end, a threaded set screw opening extending from the bottom of said groove and intersecting the opening in said boss, a set screw threaded into said opening, a spring mounted in said groove, and means 20 reacting against said set screw for securing the spring in said groove.

5. An article of manufacture comprising a governor arm having an apertured boss and a 25 spring receiving groove at one end, a threaded set screw opening extending from the bottom of said groove and intersecting the opening in said boss, a set screw threaded into said opening, a 30 spring mounted in said groove, means reacting against said set screw for securing the spring in said groove, a spring engaging projection formed at the outer end of the arm, said spring extending beyond said projection, and an eye formed in the outermost end of said spring.

6. An article of manufacture comprising a 35 governor arm having an apertured boss at one end, a threaded set screw opening intersecting the opening in said boss, a set screw threaded into said opening, a spring having an opening receiving said set screw, means reacting against 40 said set screw for securing the spring to said arm, a spring-engaging projection formed at the outer end of the arm, said spring extending beyond said projection, and an eye formed in the outermost end of said spring.

7. Governor control mechanism for a tractor or the like having a speed responsive governor including a governor shaft and a carburetor including a throttle valve, said mechanism comprising a governor actuated arm apertured to receive 50 said governor shaft, means operatively connecting said arm with said throttle valve, whereby the position of said arm determines the throttle opening of the carburetor, a spring, means fixing one end of said spring to said arm and said arm to the governor shaft, a manually 55 adjustable lever movably mounted on the tractor and adapted to retain any position of adjustment, and means connected between said manually adjustable lever and the outer end of said 60 spring.

8. Governor control mechanism for a tractor or the like having a speed responsive governor and a carburetor having a throttle valve, said mechanism comprising a governor-actuated arm 65 operatively connected to open and close said throttle valve, a fixed pivot on the tractor for said governor-actuated arm, a flexible spring member fixedly anchored at one end to said arm adjacent its pivot, a control lever connected to 70 the other end of said spring member to govern the amount of force exerted by the spring member against the arm in any given position of the latter, and means serving as a stop carried by the arm and engageable with said spring mem- 75

ber to cooperate with said control lever in limiting the open position of the throttle valve.

9. Governor control mechanism for a tractor or the like having a speed responsive governor and a carburetor having a throttle valve, said mechanism comprising a throttle rod connected with the throttle valve, a governor-actuated arm pivoted at its inner end and connected with the throttle rod, a leaf spring member anchored at 5 its inner end to the inner end of said arm, and means connected with said leaf spring member to adjust the tension exerted by the latter on said governor-actuated arm.

10. Governor control mechanism for a tractor or the like having a speed responsive governor and a carburetor having a throttle valve, said mechanism comprising a throttle rod connected with the throttle valve, a governor-actuated arm connected with the throttle rod, a leaf spring 10 member anchored at its inner end to said arm, said arm being swingable in a direction to close the throttle valve of the carburetor against the bias of said leaf spring member and engaging

the latter when moved in the other direction, whereby movement of the governor arm in said other direction is limited, and a manually set lever connected with said leaf spring member to govern the bias imposed on said governor arm 5 by said spring when said arm is moved to close said throttle valve.

11. Governor control mechanism for a tractor or the like having a speed responsive governor and a carburetor having a throttle valve, said 10 mechanism comprising a governor-actuated arm mounted for movement about a pivot on the tractor and operatively connected to open and close said throttle valve, a flat flexible spring member fixedly anchored at one end to said arm 15 adjacent its pivot and adapted to oppose closing movement of the valve, and a control lever connected with said spring member outwardly of the connection of the latter with said arm for governing the amount of force exerted by the 20 spring member against the arm in any given position of the latter.

ELMER McCORMICK.
